UNITED STATES PATENT OFFICE.

WARREN C. BEVAN, OF MALAGA, SPAIN.

DESIGN FOR A BOTTLE.

SPECIFICATION forming part of Design No. 23,550, dated August 7, 1894.

Application filed July 12, 1894, Serial No. 517,363. Term of patent 7 years.

To all whom it may concern:

Be it known that I, WARREN C. BEVAN, a citizen of the United States, residing at Malaga, Spain, have invented and produced a new and original Design for Bottles, of which the following is a specification, reference being had to the accompanying drawings, forming a part hereof.

Figure 1 is a face view of a bottle embodying my new and original design. Fig. 2 is a rear view of the same, and Fig. 3 is a sectional elevation of the bottle on the line 3—3 Fig. 2.

The bottle for the main part is in the form of an elongated cylinder having a domeshaped top, *a*, from the upper central portion of which rises the contracted neck, *b*.

Immediately above the base, and also at the junction of the dome portion with the cylindrical portion of the bottle are deep annular grooves or insets, *c*, which separate the cylindrical portion and render it more distinctive.

The front face of the bottle, from a point near the upper groove to a point near the

lower groove, and extending half way around the cylindrical portion of the bottle is perfectly plain and smooth, the smooth surface being bounded by a groove, *e*, which separates it from the rest of the bottle. The remainder of the cylindrical portion is provided with a series of grooves, *g*, crossing each other at obtuse and acute angles so as to form apparent lozenge or diamond shaped projections, *h*, the edges of which merge into the grooves, while their outer faces are practically flat having the same radial projection as the flat face before described.

Having thus described my invention, what I claim, and desire to secure by Letters Patent, is—

The design for a bottle as herein shown and described.

In testimony whereof I have hereunto set my hand this 28th day of June, A. D. 1894.

WARREN C. BEVAN.
